UNITED STATES PATENT OFFICE.

WILLIAM D. BELL, OF SLAYTON, MINNESOTA.

WEIGHT-MOTOR AND GOVERNOR MECHANISM.

SPECIFICATION forming part of Letters Patent No. 707,377, dated August 19, 1902.

Application filed October 10, 1901. Serial No. 78,214. (No model.)

To all whom it may concern:

Be it known that I, WILLIAM D. BELL, a citizen of the United States, residing at Slayton, in the county of Murray and State of Minnesota, have invented certain new and useful Improvements in Weight-Motors and Governor Mechanism; and I do declare the following to be a full, clear, and exact description of the invention, such as will enable others skilled in the art to which it appertains to make and use the same.

The invention relates to a power-transmitting device.

The object of the invention is to provide a simple, durable, and inexpensive machine of this character for converting a transmitted reciprocatory or variable rotary motion into a uniform rotary motion, the power thus received being stored for future use when needed.

With this and other objects in view the invention consists of certain novel features of construction, combination, and arrangement of parts, which will be more fully described, and particularly pointed out in the appended claims.

In the accompanying drawings, Figure 1 is a perspective view of one embodiment of a machine for carrying out my invention. Fig. 2 is a top plan view; and Fig. 3 is an end view of the axes of the two winding-drums, showing the pawl-and-ratchet connection between them and the gear-wheels carried at the ends of the drums. Fig. 4 is a detail sectional view of one of the winding-drums, its pawl and ratchet, and its gear-wheel. Fig. 5 is a detail view of certain parts composing the clutch-shipper.

Referring now more particularly to the drawings, 1 denotes the framework of the machine, and 2 and 3 denote winding-drums, each of which is provided with stub-axles journaled in suitable bearings in the framework.

4 and 5 denote beveled gear-wheels fixed to the stub-axles at one end of the drums, and 6 and 7 denote gear-wheels connected to the stub-axles at the opposite ends of the drums by pawls and ratchets 8 and 9, respectively, whereby said drums are permitted to rotate in one direction without turning their gear-

wheels and when rotating in the opposite direction will positively turn their gear-wheels.

10 denotes a drive-shaft suitably journaled in the framework of the machine and provided with loosely-mounted beveled gears 11 and 12, designed to be locked to said shaft and drive the beveled gears 5 and 4, respectively. Any suitable means may be employed for effecting this; but that shown in the accompanying drawings is preferred, and comprises a sleeve 13, having at opposite ends clutch members 14 and 15, which are adapted to be engaged with corresponding clutch members 16 and 17, carried by the gears 11 and 12. The sleeve 13 is splined to said shaft to rotate therewith and slide thereon by a pin 18, which projects through a longitudinal slot 19, formed in said sleeve.

20 denotes a rope or cable doubled upon itself and passed over one or more sets of pulleys 21 and at its bight supports a weight 22. The ends of this cable or rope are one secured to the drum 2 and the other to the drum 3.

23 and 24 denote reversing devices, which, as shown, comprise bars hinged at one end to the supporting-frame and provided with longitudinal slots 25 and 26, through which the runs of the rope or cable work.

28 denotes a clutch-shipper, which consists of a pivoted fork 29, which engages a grooved collar 30, carried by the sleeve. Rods 31 are pivoted to this lever and extend through the ends of boxes 33 and are provided with coiled springs 34, which are confined between nuts carried by the outer ends of said rods and the inner ends of the boxes. The outer ends of said boxes are connected by ropes 35, which pass under pulleys 36, secured to the framework of the machine, and through the free ends of the reversing-bars.

37 denotes a suitably-supported shaft carrying at one end a gear-wheel 38, which is constantly in mesh with the gear-wheels 6 and 7, and provided at its opposite end with a gear-wheel 39, which meshes with a gear-wheel 40, carried by a shaft 41 to be driven.

The operation of the device is as follows: Assuming the parts to be in the position shown in Fig. 2 and power supplied from any suitable source to the shaft 10, the power from

said shaft will be transmitted through the gears 5 and 11 to the drum 2, thus rotating said drum to wind up the rope or cable thereon, and as this drum is rotated the drum 3, 5 upon which the cable was previously wound, will be unwinding, and in this unwinding movement, its gear-wheel 6 being locked to it, said gear-wheel will transmit the motion from said drum, which motion is steady and 10 uniform, due to the pull of the weight, to the gear 38, and through the intermediate gearing to the shaft 41, from which the power is transmitted to the machine to be driven. It is of course understood that the weight is of sufficient gravity as to be equal to the occasion 15 of running the machine to be driven, and in order to control the movement of the shaft 41 any suitable form of governor or brake (designated by the letter *x*) may be employed 20 for the purpose of limiting the speed of the power-transmitting device, so that the machine driven will be under complete control, or, if desired, the machine driven may be equipped with such a governor or brake. It 25 being assumed that the machine to be driven is in operation and power is at the same time being transmitted to the shaft 10 and the machine to be driven is under the complete control of its brake or governor, the rope or cable 30 20 will be successively wound and unwound from the drums 2 and 3 and the weight 22 will be bobbing up and down and acting somewhat in the nature of a governor to transmit the variable motion received by the 35 shaft 10 from its source of power to the drums 2 and 3, and thus the weight will cause a uniform power to be transmitted to the shaft 41 to drive the machine; but of course the power transmitted to the machine will be 40 considerably less than that received by the shaft 10, owing to the loss of power due to friction. Now assuming that the machine to be driven is at a state of rest, or, in other words, it is out of operation for the time being, 45 it is evident that when power is transmitted to the shaft 10 and the shaft 41 is held against rotation it will elevate the weight to its highest point, and thus the weight will be retained at that point until it is desired to 50 transmit the power stored by the elevated weight to the machine to be driven. It will thus be seen that the device when thus used acts as a power-storing device in that it stores power which would otherwise be wasted, and 55 the stored power is capable for use for driving machinery when it is so desired. Now coming back to the operation of the machine when it is in the position shown in Fig. 2 and power is transmitted to the shaft 10 and 60 through the gear-wheels 5 and 11 to the drum 2, said drum will be rotated to wind up the rope or cable, and as this drum is rotated the drum 3, upon which the cable was previously wound, will be unwinding, and in its 65 unwinding movement, its gear-wheel 6 being locked to it, said gear-wheel will transmit the motion from said drum, which motion is

steady and uniform, due to the pull of the weight, and this motion will be transmitted to the gear 38 and through the intermediate 70 gearing to the shaft 40. In this rotation of the gear 38 the gear 7 of the drum 2 will slip upon its stub-shaft in a direction opposite to that in which the drum is being rotated. As the rope continues to unwind from the drum 75 3 a knot *a* in the rope will come in contact with the reversing-bar 24 and will elevate said bar, thus moving the clutch-sleeve 13, with its clutch member 14, from engagement with the clutch member 16 and throwing its clutch 80 member 15 into engagement with the clutch member 17 of the gear 12, so that the movement from said shaft 10 will be transmitted to the drum 3 to wind the rope or cable thereon, and the drum 2 will be released to permit 85 it to unwind under the action of the weight 22, and thereby rotate its wheel 7, which being in mesh with the wheel 38 will transmit its motion to the shaft to be driven, the wheel 6 now slipping or rotating in the opposite direction to the drum 3, as did the wheel 7 when said drum 2 was winding up the cable. 90

In Fig. 2 I have shown a pump-rod (denoted by the letter *b*) for operating the shaft 10. This rod, as shown, is provided with a 95 pawl *c*, which engages a ratchet-wheel *d*, fixed to said shaft. A stop-ratchet *e* is employed to prevent retrograde movement of said shaft.

In Fig. 1 I have shown the power as being 100 derived from a rotary source, *g* denoting a rotary shaft for transmitting the movement to the shaft 10. The shaft *g* is provided with a pinion *h*, which is in mesh with the gear-wheel *i*, secured to the end of the shaft 10. 105 The pinion *h* is loosely fixed upon the shaft *g* and is provided with a clutch member *h'*, which is adapted to engage a clutch member *h''*, splined to the shaft *g*. When these two clutch members are locked together, the power 110 from the shaft *g* will be transmitted to the shaft 10. *j* denotes a stopping device which 115 consists of a lever *k*, having one of its ends in the path of movement of the weight 22. A rope *l*, rove around suitable pulleys *m*, connects the opposite end of the lever *k* to a pivoted crank-clutch shipper-lever *o*. It is evident that when the weight 22 is elevated and strikes the free end of the lever *k* it will elevate said end and, through the cord or rope 120 11, disengage the pinion *h* from gear-wheel *i*, thus stopping the power if it be supplied to the shaft 10 faster than it can be taken from the shaft 41, and thereby preventing injury to the power-transmitting device, or in the event 125 that the machine to be driven is held in a state of rest or the brake applied to the shaft 41 the power taken on at the shaft 10 will be likewise stopped when the weight 22 strikes the lever *k*. The power-transmitting device 130 will then be in condition for immediate future use for transmitting a uniform power to the machine to be driven.

From the foregoing description, taken in

connection with the accompanying drawings, the construction, mode of operation, and advantages of the invention will be readily understood without requiring an extended explanation.

5 Various changes in the form, proportion, and details of construction may be made within the scope of the invention without departing from the spirit or sacrificing any of the 10 advantages thereof.

Having thus described my invention, what I claim, and desire to secure by Letters Patent, is—

1. In a machine of the character described, 15 the combination with suitably-journaled drums, of a rope or cable having its ends attached to said drums, a weight supported by said rope, a drive-shaft, and a shaft to be driven, gearing for transmitting motion from 20 the drums in alternation, and means for applying the power to said drums from the drive-shaft, in alternation, substantially as set forth.

2. In a machine of the character described, 25 the combination with suitably-journaled drums, of a rope or cable having its ends attached to said drums, a weight supported by said rope, a drive-shaft and a shaft to be driven, gearing for transmitting motion from 30 the drums in alternation, means for applying the power to said drums from the drive-shaft, in alternation, and means for automatically shifting said first-named means, substantially as set forth.

3. In a machine of the character described, 35 the combination with drums, of a rope or cable, the ends of which are secured to said drums, a weight supported by said rope or cable intermediate its ends, gear-wheels having a pawl-and-ratchet connection with said drums, a shaft to be driven, a gear constantly in mesh with the gears carried by said drums and geared up with the shaft to be driven, and means for rotating said drums in alter-

45 nation, whereby as one drum rotates to wind up the rope or cable, the other drum may rotate to unwind the rope or cable, substantially as set forth.

4. In a machine of the character described, 50 the combination with drums, beveled gear-wheels fixed to one end of said drums, gear-wheels having a pawl-and-ratchet connection with the opposite ends of said drums, a shaft to be driven, gearing interposed between the shaft to be driven and the last-named gear-wheels, a drive-shaft, mechanism for transmitting the movement from said drive-shaft to either one of the beveled gears, and means carried by the rope or cable for automatically actuating said mechanism, substantially as 55 set forth.

5. In a machine of the character described, 60 the combination with suitably-journaled drums, of gear-wheels carried thereby, a rope having its ends connected to said drums, a weight supported by said rope or cable, a drive-shaft, pinions loosely mounted on said drive-shaft and in mesh with said beveled gears, a clutch for locking either pinion to rotate said drive-shaft, pivoted bars having 65 slots through which the rope passes, knots formed upon said rope of greater diameter than the slots, a clutch-shipper lever, and a connection between the clutch-shipper lever and the bars whereby, when one of said bars 70 is elevated by the engagement therewith of one of the knots, the clutch will be shifted to throw one of the pinions out of operative engagement and the other pinion into operative engagement, substantially as set forth. 75

In testimony whereof I have hereunto set my hand in presence of two subscribing witnesses.

WILLIAM D. BELL.
